UNITED STATES PATENT OFFICE.

JOHN B. GLOVER, OF MATTOON, ILLINOIS.

INCUBATOR.

1,355,602.

Specification of Letters Patent. Patented Oct. 12, 1920.

Application filed July 29, 1919. Serial No. 314,060.

To all whom it may concern:

Be it known that I, JOHN B. GLOVER, a citizen of the United States, and a resident of Mattoon, in the county of Coles and State of Illinois, have invented certain new and useful Improvements in Incubators, of which the following is a specification.

My invention is an improvement in incubators, and has for its object to provide mechanism in connection with incubators, for providing uniform heat for the eggs in the incubator, and for supplying at all times a sufficient supply of heat, together with means for regulating the same to prevent overheating.

In the drawings:

Figure 1 is a perspective view of an incubator provided with the improvement,

Fig. 2 is an end view of the heater with parts in section,

Fig. 3 is a horizontal section through the incubator casing above the heater,

Fig. 4 is a vertical section at the draft tube of the heater.

The present embodiment of the invention is shown in connection with an improved incubator of usual form, comprising the casing 1 for receiving the eggs and heater, and an oil lamp 2 for supplying heat to the heater. The improved heater consists of a tubular structure comprising an upper portion 3 for containing water, and a lower portion 4 for the heated air from the lamp, the two chambers or compartments 3 and 4 being combined into a single substantially cylindrical structure.

The parts are separated by a horizontally disposed partition 5 of sheet metal, arranged as shown in Fig. 2, in sinuous form. The sheet from which the partition is formed, is bent as shown to form a series of grooves extending longitudinally of the casing, the said grooves being of considerable depth so that the water at the partition is separated into a number of relatively thin layers, between each pair of which there is a passage for heat, the arrangement being such that all of the layers are inclosed by heated air on two sides.

In the present instance, this tubular structure is formed by bending a sheet of metal to form the partition 5, and afterward to form the outer inclosing walls of the chamber 3, the edges of the sheet being seamed as shown at 5^a at the top of the casing. The compartment 4 is formed by securing a

curved strip at the underside of the chamber 3, the edges of the strip being soldered or otherwise secured to the outer walls of the chamber 3.

This tubular casing 3—4 extends through the end walls of the incubator casing as shown in Figs. 3 and 4, and a draft tube 6 is connected with one end of the said casing. The heater, that is, the oil lamp 2 is connected with the other end, by means of a T 7. This T as shown more particularly in Figs. 1 and 4 has its body portion vertical and its lateral branch connected with the adjacent end of the tubular casing 3—4.

The chimney 8 of the lamp is connected with the lower end of the body portion, and a damper 9 which is controlled by a thermostat of usual construction is arranged at the upper end of the body. This thermostat as shown in Fig. 3 comprises the usual wafer 10 which is connected to the damper by lever mechanism indicated at 11, to open and close the damper in accordance with the temperature of the interior of the incubator.

The chamber 3 which may be considered as the boiler has a filling and expansion nipple 12 outside the casing, and at the other end outside the casing there is a normally closed drain opening 13. The heated air from the lamp passes through the chamber 4 of the boiler, and between the side walls of the grooves of the partition 5, eventually escaping by way of the draft tube 6, and the water in the chamber 3 is heated by the heated air. In order to evenly distribute the heat throughout the incubator casing, circulation pipes are connected with the casing 3—4.

These pipes are shown more particularly in Figs. 2 and 3, each consisting of a body 14 and arms 15 and 16, the bodies extending substantially parallel with the casing in spaced relation, while the arms 15—16 are connected with the casing. Referring to Figs. 2 and 4, it will be seen that the arms 15 are connected to the casing 3—4 at a higher level than are the arms 16, so that as the water is heated in the chamber 3, it will pass out by way of the arms 15 through the bodies 14, and will return by way of the arms 16 to the chamber 3, it being understood that the arms 15—16 communicate with the chamber 3.

In practice, the incubator is well ventilated, an unusual number of openings 17 being provided for admitting cool air to the

interior of the casing, and these openings may be closed by suitable dampers not shown. In operation, with the lamp in place, it will be evident that the heated air 5 will pass from the lamp through the chamber 4, eventually passing out of the chamber by way of the elbow 6. The water in the chamber 3 will become heated first at that end adjacent to the lamp. This heated 10 water will pass out through the arm 15, and the bodies 14 of the circulation pipes, and will return to the chamber 3 by way of the arms 16 at the end adjacent to the lamp. Thus there will be a continual circulation of 15 water. As the water cools after its return to the chamber 3 it will sink to the bottom of the said chamber and will be reheated going again into the circulation.

It will be noticed that all of the joints 20 of the heater are on top, where they are easily accessible for repair, and where in case of leakage there will be no dripping on the eggs and into the incubator.

I claim:—

25 1. In an incubator, a water heater comprising a central tubular structure divided by a horizontally disposed partition into an upper water chamber and a lower air chamber, and water circulation pipes at the opposite sides of the casing and communicating with the water chamber at the ends thereof, said circulation pipes opening out of the water chamber at a higher level than at their entrance, the partition being bent longitudinally into a series of relatively deep 30 grooves to divide the water into relatively thin layers, said tubular structure having means at one end for connection with a

lamp, and having a draft pipe at the other end.

40 2. In an incubator, a water heater comprising a central tubular structure divided by a horizontally disposed partition into an upper water chamber and a lower air chamber, and water circulation pipes at the opposite sides of the casing and communicating with the water chamber at the ends thereof, said circulation pipes opening out of the water chamber at a higher level than at their entrance, the partition being bent 45 longitudinally into a series of relatively deep grooves to divide the water into relatively thin layers.

45 3. In an incubator, a water heater comprising a tubular structure divided by a substantially horizontally disposed partition into an upper water chamber and a lower heating chamber, and water circulation pipes connected with the water chamber the partition being bent into a series of 50 relatively deep folds spaced apart from each other to divide the water into relatively thin layers.

4. A water heater for incubators comprising a water chamber formed from sheet 65 metal bent to form a concave and a convex surface, the connection between the edges of the sheet metal being at the center of the convex surface, and the concave surface being bent to form a series of relatively deep 70 longitudinally extending grooves, and an inclosing plate extending between the side edges of the chamber and forming an inclosed heating chamber below the water chamber.

JOHN B. GLOVER.
